CLAIM

The ornamental design for a display screen or portion thereof with graphical user interface, as shown and described.

DESCRIPTION

1. Display screen or portion thereof with graphical user interface

1.1 : Front

1.2 : Back

1.3 : Left

1.4 : Right

1.5 : Top

1.6 : Bottom

1.7 : Partial enlarged front view, provided for clarity of illustration

The outermost broken lines showing an electronic device are included to illustrate environmental structure; the dashed broken lines inside the solid line display screen show portions of the graphical user interface; the top and bottom most horizontal dashed broken lines in reproduction 1.7 indicate the limits of the enlarged partial view; all broken lines form no part of the claimed design.

1 Claim, 7 Drawing Sheets
